UNITED STATES PATENT OFFICE

JAMES R. HUGHES, OF SOUTH BEND, INDIANA, ASSIGNOR TO THE PIERCE-ARROW MOTOR CAR COMPANY, OF BUFFALO, NEW YORK, A CORPORATION OF NEW YORK

DESIGN FOR A COMBINATION OF FENDERS, PARKING LAMPS, HEAD LAMPS AND BRACKETS THEREFOR FOR VEHICLES

Application filed September 6, 1929. Serial No. 32,682. Term of patent 14 years.

To all whom it may concern:

Be it known that I, JAMES R. HUGHES, a citizen of the United States of America, and a resident of South Bend, in the county of St. Joseph and State of Indiana, have invented a new, original, and ornamental Design for a Combination of Fenders, Parking Lamps, Headlamps, and Brackets Therefor for Vehicles, of which the following is a specification, reference being had to the accompanying drawings, forming a part thereof.

In the drawings, Figure 1 is a perspective view of a combination of fenders, parking lamps, headlamps and brackets therefor for vehicles showing my new design, and Figure

2 is a front elevational view thereof. My invention consists particularly in the use of relatively small headlights, of the configuration shown upon the fenders in combination with the pair of intermediate larger headlights of a similar configuration but of larger size.

I claim:

The ornamental design for a combination of fenders, parking lamps, headlamps and brackets therefor for vehicles substantially as shown and described.

Signed by me at South Bend, Indiana, this 3rd day of September, 1929.

JAMES R. HUGHES.
